UNITED STATES PATENT OFFICE

164,483

COPYHOLDER

Marian A. Flannery, North St. Paul, Minn., assignor to Bankers Box Company, Chicago, Ill., a corporation of Illinois

Application September 26, 1950, Serial No. 12,356

Term of patent 14 years

(Cl. D74—1)

To all whom it may concern:

Be it known that I, Marian A. Flannery, a citizen of the United States, residing in North St. Paul, in the county of Ramsey and State of Minnesota, have invented a new, original, and ornamental Design for a Copyholder, of which the following is a specification, reference being had to the accompanying drawings, forming part thereof, in which:

Fig. 1 is a perspective view taken from one side and somewhat from the front end of a copyholder, embodying my new and ornamental design;

Fig. 2 is a side elevational view thereof;

Fig. 3 is another perspective view of the copyholder taken from the same side as Fig. 1 and somewhat from the rear end; and

Fig. 4 is a top plan view of my copyholder as it appears with the parts folded together.

I claim:

The ornamental design for a copyholder, substantially as shown.

MARIAN A. FLANNERY.
